UNITED STATES PATENT OFFICE

2,666,353

DEVICE FOR TURNING THE PAGES
OF MUSICRichard Graves, Cape Coast, Gold Coast,
British West Africa

Application March 20, 1951, Serial No. 216,564

1 Claim. (Cl. 84—520)

1 To all those who play music by sight, it is well known that the need to turn the pages of the music by hand is a disadvantage, necessitating as it does the removal of a hand from the instrument, so that the continuity of the performance is interrupted. The chief object of the present invention is to overcome this disadvantage and to provide a simple and efficient device whereby the pages of the music may be automatically turned, as and when required.

The device for turning the pages of music according to the present invention comprises a plurality of arms adapted to be attached to and to project from the sides of the pages to be turned, in combination with a pivotally mounted operating lever adapted to be swung about its pivot on operation of a foot or other pedal to engage with the projecting portion of the arm attached to the page to be turned to flick the arm, and hence the page, over.

The operative end of the said lever is preferably pivotally mounted in such a manner that it is free to move only upwardly with respect to the main body of the lever to enable it to pass to the back of the next page-attached arm on return of the foot pedal, ready for turning the next page when required.

In order that this invention may be the more clearly understood and readily carried into effect, reference may be made to the accompanying drawings, which illustrate, by way of example, one convenient embodiment of this invention as applied to the type of music stand used, for example, by violin players, and in which:

Figure 1 is a perspective view of the apparatus mounted on such a stand.

Figure 2 is a diagrammatic view illustrating the manner in which the device operates.

Figure 2 is a diagrammatic view illustrating the manner in which the operating lever re-sets itself after turning a page, ready to turn the next page when required.

Referring now to the accompanying drawings, the apparatus for automatically turning pages of music therein illustrated comprises a number of arms 10, one for each of the pages of music which it is desired to turn, said arms being adapted to be attached to the pages 11 in any suitable manner. Conveniently the arms 10 may be formed as elongated clips adapted to fit about the page with which the arm is to be used. The arms 10 are adapted to extend into the music up to, or substantially up to, the spine so that they act as true levers to turn the page when they move about their inner ends as pivots. The

5 arms 10 are of such a length that they jut out beyond the edge of the page 11 and outside the page they are provided with upstanding bridges 12, the arms behind the bridges being gapped, as will be seen more clearly in Figure 2. In order to turn a page to which an arm has been attached it is merely necessary to impart a flick to the bridge 12, when the arm 10 will swing about its inner end as a pivot taking with it the page, it being understood, of course, that the piece of music is firmly attached to the music stand 13 in a suitable manner.

10 Freely mounted on a pivot 14 carried at a suitable part of the music stand 13 is an operating lever 15 the lower end of which extends downwardly, in the embodiment illustrated, and lies behind the bridge of the uppermost arm. The lever 15 is connected by means of a link 16 to a foot pedal 17 located at an appropriate position 15 relative to the stand. It will be seen that a sharp depression of the foot pedal 17 will cause the lever 15 to move sharply upwards and so flick over the page, through the intermediary of the arm 10 as explained above. Due to the gap between the bridge in the arm, the arm 10 can move away from the end of the lever 15 after the initial impulse.

15 When the foot pedal is released the lever 15 returns to its original position and re-sets itself relative to the next lower arm 10 ready to turn the page to which it is attached on the next depression of the foot pedal. To this end, the lower portion 15a of the operating lever 15 is hinged to the main portion of the arm so that it is free to move with respect to the same only upwardly. When the lever 15 returns, its end 15a snaps over the bridge 12 of the next arm and becomes 20 located under that bridge (as shown in broken lines in Figure 3) ready for the next operation of the foot pedal.

25 The bridges 12 act as spacers to keep the pages of the music apart and to ensure that they are turned individually and successively.

30 In some cases, for example when the device is used to turn the pages of music on a piano or organ it may be found inconvenient to link the pedal to the operating lever by a rod in the manner shown in the drawings. In this case depression of the pedal may be caused to send a pulse of compressed air along a tube extending from the pedal to a plunger connected to the operating lever. Actuation of the operating lever is then effected by the compressed air instead of directly as in the embodiment shown in the drawings. Again, where the feet are used for

playing the instrument, for example an organ, the pedal may be actuated by the knee.

The operating lever 15 need not be mounted with respect to the music stand in the manner indicated in the drawings. All that is necessary is that it should be so mounted on the music stand as to impart the flick to the outstanding portion of the top arm when the foot pedal is depressed.

If desired the length of the arms 10 and the length of the operating lever 15 may be adjustable in order to adapt the device to music having different sizes of page and to music stands of different sizes and types.

I claim:

A device for automatically turning pages of music whilst permitting the retention of the player's hand upon the instrument being played, including a plurality of arms, each arm being formed as an elongated clip and embracing a single page, each arm being of a length sufficiently great to project beyond one edge of said page, a bridge erected on said projecting portion of each arm, a lever arm pivoted near one end and having the other end for engaging said bridge, means at said engaging end including an ancillary relatively short arm, means pivoting said ancillary arm upon said lever arm at a point relatively close to the engaging end thereof, means allowing said ancillary arm to swing upwardly through an angle sufficient to pass the upper portion of said bridge when said lever arm is moving down relatively to said bridge, whereby said ancillary arm enters into said bridge, means blocking the downward swinging of said ancillary arm when said lever arm is moved upwardly,

whereby said upward movement of said lever arm will compel said bridge to move upwardly until the angular motion of said lever arm about the pivoted end thereof shortens the effective distance to which said ancillary arm enters said bridge until it assumes a negative value, whereby said ancillary arm becomes disengaged at a predetermined angular position from said bridge and allows said bridge to continue upward movement by virtue of the inertia acquired whilst said lever was moving the bridge upwardly and was mechanically coupled thereto via the intermediary of said ancillary arm, said coupling thereby constituting a one-way valve action, and power supply means for raising said lever arm and for allowing the descent thereof, said power supply means including a substantially vertical push rod pivoted at the upper end to said lever arm at a point intermediate the extremities thereof and nearer the pivotal point thereof, and foot pedal means engaging the lower end of said push rod.

RICHARD GRAVES.
